(57) **CLAIM**

The ornamental design of a multipurpose bag, as shown and described.

DESCRIPTION

FIG. 1 is a top perspective view of a multipurpose bag showing my new design;

FIG. 2 is a top plan view thereof;

FIG. 3 is a bottom plan view thereof;

FIG. 4 is a left elevation view thereof, the right elevation view being identical in appearance; and,

FIG. 5 is a front elevation view, the rear elevation being identical in appearance.

The broken lines showing the bottom portion of the bag are for the purposes of illustrating environment and form no part of the claimed design.
